[57] CLAIM

The ornamental design for a rack for dispensing articles, as shown and described.

DESCRIPTION

FIG. 1 is a top, front and left side perspective view of a rack for dispensing articles, showing my new design;

FIG. 2 is a top plan view thereof;

FIG. 3 is a right-side elevational view thereof, the left-side being a mirror image thereof;

FIG. 4 is a front elevational view thereof;

FIG. 5 is a rear elevational view thereof;

FIG. 6 is a bottom plan view thereof.

FIG. 1

FIG. 2

FIG. 3

FIG. 4

FIG. 5

FIG. 6
